US00D912791S

(12) **United States Design Patent** (10) **Patent No.:** **US D912,791 S**
(45) **Date of Patent:** **** Mar. 9, 2021**

(54) **PERSONAL HEATING OR COOLING DEVICE**

(71) Applicant: **Airwirl, LLC**, North Palm Beach, FL (US)

(72) Inventors: **Steve A. Herweck**, Wellesley Hills, MA (US); **Dana Herweck**, Wellesley Hills, MA (US); **Michael McCarthy**, Palm Beach Gardens, FL (US)

(73) Assignee: **Airwirl, LLC**, North Palm Beach, FL (US)

(**) Term: **15 Years**

(21) Appl. No.: **29/672,323**

(22) Filed: **Dec. 4, 2018**

(51) LOC (13) Cl. **23-04**

(52) U.S. Cl.

USPC **D23/355**

(57) **CLAIM**

The ornamental design for the personal heating or cooling device, as shown and described.

DESCRIPTION

FIG. 1 is a front plan view of the personal heating or cooling device;

FIG. 2 is a left side plan view of the personal heating or cooling device;

FIG. 3 is a rear plan view of the personal heating or cooling device;

FIG. 4 is a right side plan view of the personal heating or cooling device;

FIG. 5 is a top plan view of the personal heating or cooling device;

FIG. 6 is a bottom plan view of the personal heating or cooling device;

FIG. 7 is a front right side elevated isometric view of the personal heating or cooling device;

FIG. 8 is a front left side elevated isometric view of the personal heating or cooling device;

FIG. 9 is a bottom right side isometric view of the personal heating or cooling device;

FIG. 10 is a bottom left side isometric view of the personal heating or cooling device; and,

FIG. 11 is a rear left side elevated isometric view of the personal heating or cooling device.

1 Claim, 6 Drawing Sheets
